UNITED STATES PATENT OFFICE.

HERVEY W. FOWLER, OF CHICAGO, ILLINOIS.

MACHINE FOR ROLLING CAR-WHEELS.

SPECIFICATION forming part of Letters Patent No. 351,430, dated October 26, 1886.

Application filed October 16, 1885. Serial No. 180,066. (No model.)

To all whom it may concern:

Be it known that I, HERVEY W. FOWLER, of Chicago, in the county of Cook and State of Illinois, have invented certain new and useful Improvements in Machines for Rolling Car-Wheels; and I do hereby declare that the following specification, taken in connection with the drawings furnished, and forming a part of the same is a clear, true, and complete description of my invention.

The main objects of my invention are to economically correct such peripheral variations as are liable to exist in a solid steel-wheel casting, and also to condense and toughen the tread of the wheel. My machines can, however, be employed, if desired, for rolling the rims of other kinds of car-wheels.

So far as I know, steel car-wheel castings, if practically rolled at all, have heretofore been so rolled as to increase the diameter of the casting, and such machines as have heretofore been devised would inevitably produce a finished car-wheel of greater diameter than the original casting. My machines do not thus increase the diameter of the original casting, but reduce it correspondingly to the degree of condensation and displacement of the metal at the flange and tread of the wheel. By said prior method the web of the wheel has also been rolled simultaneously with the tread; but by my method the wheel at and adjacent to its rim is only operated upon, although the web might be more or less condensed by additional co-operating mechanism without materially affecting my invention.

My machines are adapted to properly operate upon a car-wheel, whether it be wholly cold or the rim heated and the web cold, or the entire wheel heated; but of course the results would be more or less varied in harmony with said several conditions. The method or process involved is believed to be novel, as well as the cast-steel car-wheel produced thereby, and I contemplate making the same the subject of a separate application for Letters Patent. (See Serial No. 200,683.)

My machine is believed to be novel, in that it embodies the combination of a series of circularly-arranged and positively-driven rolls, each having a pair of flanges or collars and a rolling-face, corresponding to the periphery of a finished car-wheel, and a housing for said

rolls which affords a central space for the free reception of a car-wheel, so that its periphery may be properly engaged by the several rolls. 55 The two collars or flanges on each roll constitute means whereby the rim of a car-wheel is accurately trued up and the metal confined against undue expansion between the inner and outer faces of the rim. For admitting 60 and discharging a car-wheel, and for gradually increasing the rolling pressure thereon, the rolls are radially adjustable, and are locked by adjusting or temper screws, as is common in rolling-mills, and said screws are arranged 65 to be simultaneously operated. I also employ driving-gearing in a separate housing, and connect with the rolls by means of coupling-bars. I have also provided an axial clamp, by which, whenever desirable, the 70 web of a wheel may be supported during the rolling operation, and I have also provided means whereby said wheel may, when desired, be axially mounted during the rolling operation.

I am aware that in United States Letters Patent to Hartson, No. 11,243, July 11, 1854, there was disclosed a machine for roll-forging wrought car-wheels from plate-iron disks. Said machine had a pair of rolls having the contour of a car-wheel tread and flange, and these co-operated with interior rolls; but none of these rolls were positively driven, but were frictionally engaged by the wheel-disk, which was chucked upon a positively driven shaft; 85 also that in United States Letters Patent to Vanstone, No. 37,368, January 6, 1863, a machine was disclosed embodying two rolls which had the contour of a car-wheel tread and flange, and which were positively driven. In Vanstone's machine but one of said rolls was adjustable, and they co-operated with an anvil-roll and a hammer in developing a rim and flange at the periphery of a plate-iron disk; also, that British Letters Patent, No. 1,085, of 1861, disclosed a series of rolls circularly arranged and radially adjustable by means of many pieces of shafting and beveled gears, but without any internal supporting device, and also without the contour of the tread and flange of a 90 car-wheel, but organized specially for reducing the diameter of welded-iron rings, and for thickening worn rails. Neither of these prior machines are practically suited for my

purposes, and I make no claim to any specific features of construction therein disclosed, nor to any such combinations as were disclosed in any of said Letters Patent.

5 I am also aware that British Letters Patent, No. 93, of A. D. 1856, discloses a variety of machines for rolling the outer surfaces of tires for car-wheels, and for preparing the wheels to receive the tires thereafter to be 10 rolled. One of the machines shown and described in said Letters Patent embodied three positively-driven rolls, but the latter had but one flange or collar, and hence said rolls had no capacity for resisting the lateral expansion 15 of the tires, whereas in my machines special provision is made for enabling each roll to laterally confine the rim of a wheel against lateral expansion during the rolling operation.

20 To more particularly describe my invention, I will refer to the accompanying drawings, and after describing the machines therein illustrated the features deemed novel will be designated in the several clauses of the 25 claims hereunto annexed.

Figure 1 is a side view of one of my machines in a desirable form, with its driving-gearing. Fig. 2 is a front view of said machine. Fig. 3 is a sectional view of the machine on line *x*, Fig. 2, and illustrates a car-wheel in position for rolling. Fig. 4, in section, illustrates a clamp applied to a wheel preparatory to rolling, and a spindle to serve as the axis of said clamp, so that a car-wheel 30 can be detachably mounted centrally in the roll-housing. Fig. 5 illustrates one of the driven rolls with its box and a portion of the housing. Fig. 6 illustrates one of the driven rolls, its box or bearing, its adjusting or temper screw, and a part of the pinion thereon. Fig. 7 illustrates, in section, portions of the frame and of the controlling-gear by which the adjusting or temper screws are controlled. Fig. 8 illustrates, partially in front view and 45 partially in section, one of my machines having a set of five driven rolls, with a car-wheel in position for rolling. Figs. 9 and 10, respectively, illustrate a portion of a car-wheel casting and the same after it has been operated upon by one of my machines.

The roll-housing A may be variously constructed, according to the number of circularly-arranged rolls B which may be desired. As here shown, four rolls are arranged to 55 bear against the tread of a car-wheel, C, at practically equidistant points. While I deem it desirable to employ at least four rolls, a still greater number can be sometimes used to advantage, and five are shown in the machine illustrated in Fig. 8. In some cases three of such rolls need only be employed, and then two of them would preferably be so located as to support the wheel on its edge and the third roll above, so as to locate the rolling-points properly equidistant from each other. In some other cases, as for 65 very light work, two of such rolls may be re-

lied upon, if said rolls be positively driven, and both are adjustable toward and from a common center; but then the car-wheel or 70 blank should have an axial support, while with three or more rolls said support may or may not be employed, because the rolls will be circularly arranged and afford a concentric matrix, in which the blank can be confined concentrically while free to rotate.

75 The roll-housing A has for each roll B a radially-slotted bracket, *a*, and each roll is mounted in a box, *b*, fitted to slide truly in one of said brackets, and each box is provided with a temper or adjusting-screw, *c*, tapped into the end of the box and journaled in the outer end of a bracket. For simultaneously and evenly controlling the temper screws each has a beveled pinion, *d*, on its outer end, and 80 these all mesh with a large bevel-rim gear, *e*, mounted upon a large annular hub, *f*, at the rear of the housing, and confined to its bearings by means of a collar, *g*, secured to the hub by means of bolts *g'*, as clearly shown in 85 Figs. 3 and 7. For some kinds of light service each adjusting or temper screw might be operated by hand, or if all were to be operated simultaneously for light work the large controlling gear could be rotated by hand; 90 but for general service I apply power thereto by way of a pinion, *h*, mounted on a shaft which can be slowly driven, as by means of a worm-gear, for instance, or by means of a pulley driven by a belt, which can freely slip whenever the desired pressure on the temper-screws 95 is exceeded.

100 In the back plate of the housing there is a central opening, *i*, to serve as a support for a readily-detachable spindle, *k*, whenever an axial support is desired for a car-wheel, C, as 105 illustrated fully in Figs. 2, 3, and 4, said spindle being longitudinally slotted near its outer end to receive a key, *l*, whereby two clamping disks or cheeks, *m m*, may be caused to 110 embrace a portion of the web of a wheel, and also, when desired, to afford an interior support or abutment for the rim of a wheel during the rolling operation. The spindle *k* may 115 or may not be made to serve as an axial bearing, as may be desired. When said spindle is mounted in a hub, *k'*, and so as to revolve therein, and the latter is rigidly mounted at the center-hole, *i*, in the housing, it will serve 120 as an axial bearing, and, if desired, an outer detachable bearing for said spindle may also be used. On removing the hub *k'* the collar *k* on the spindle will still serve as a face between which and the key the disks or cheeks 125 *m m* will be clamped.

130 The gearing-housing D, as shown in Fig. 1, is parallel with the roll-housing, and embodies a central driving-gear on the shaft *n*, to which power is applied. Surrounding the driving-gear on shaft *n* are four roll-pinions, *o*, each being connected with its roll B by a socketed coupling-bar, *p*, in the usual manner, thus enabling the rolls to be properly operated at any possible adjustment, and admitting of their

radial movements while in motion. As shown in Fig. 1, the gearing is adapted to a four-roll machine; but it can obviously be employed for driving one, two, or three of said rolls, and it 5 would be merely enlarged for operating the five-roll machine shown in Fig. 8.

Both of the prior car-wheel machines hereinbefore referred to were organized to develop flanged rims on plate-iron disks, and in one 10 the disk could only be inserted and the wheel removed edgewise, and in the other it could be inserted flatwise and similarly removed. In the one case, however, the disk was essentially clamped between centering-cheeks, which were 15 fixtures in the machine, and in the other the disk was essentially chucked upon a driving-shaft; but with my machine the wheel-blank can be sometimes worked without clamps and without an axial support—but both are sometimes 20 required; and it will be seen that neither my clamp nor my axial support are fixtures in the machine, and therefore a blank can be clamped by me outside of the machine, then placed therein, and the finished wheel 25 moved with the clamp still attached thereto, thus with two or more clamps enabling the machine to be operated without that loss of time inevitably incident to clamping or chucking in the use of both of said prior machines.

Referring now to the oppositely-located rolls B, it will be seen in Fig. 5 that each has end flanges or collars, b', between which the two edges of the car-wheel will be snugly embraced; also, a groove, b², for the reception of the flange 30 of the wheel, and a face, b³, for engaging with the tread of the wheel. The collars or flanges b' b' on each roll enable the latter to effectually condense the metal at the periphery of a car-wheel in radial and peripheral lines, because, 35 during the rolling operation, the metal in the rim is confined between said flanges against lateral expansion.

Preparatory to rolling some castings, I prefer that the rim portion should be fairly well 40 heated, and the hub and web so far free from heat that the metal will not be unduly softened thereby. A casting may, however, be taken from the mold while still hot and operated upon, if care be taken to properly cool 45 the central portion, or even without that precaution, if the clamping-cheeks m, Fig. 4, be used.

As a rule, I prefer the rolls B so arranged 50 that an axial support for the car-wheel C may be dispensed with, and I have referred to said rolls as being oppositely located, and by this I mean that said rolls are so located with reference to each other that each exerts an opposing rolling force against that of some one 55 or more rolls which are located substantially opposite thereto, and while in most cases it may be desirable to have said rolls exactly equidistant, it is sometimes desirable to have them 60 variably spaced.

Instead of relying upon the original heat in 65 the car-wheel casting, I can usually obtain better results by taking a cold casting and heat-

ing it in an annularly-chambered furnace, which will thoroughly heat the rim of the wheel and keep the center sufficiently cool. 70 When a casting has been thus specially heated, the clamp may or may not be used, according to the dimensions of the wheel and the degree of heat at its hub and web. In some cases 75 a cold casting may be entirely heated and rolled, if due care be given to centrally clamp- ing it, as described.

In rolling the tread of a wheel, the reduction in diameter may be readily gaged by means of suitable callipers, and when an axial support for the car wheel is employed, the careful control of the several rolls will enable the diameter to be accurately gaged. 80

A cast-steel car-wheel with its rim or tread rolled and condensed, as in my machine, and 85 by the method described, is a novelty in the trade, and has special value because of the fact that the tread is thoroughly condensed, and is practically circular, and is consider- ably less in diameter than the original casting. 90 Such wheels can be produced at much less cost than the well-known steel-tire wheels, or others of a composite structure, and yet mine are capable of similarly extended service with equally desirable results, and in many cases 95 unequally-worn wheels can be re-rolled in my machines and rendered suitable for further and efficient service.

In Fig. 9 I have accurately illustrated a portion of the rim of a steel car-wheel casting, 100 and in Fig. 10 I have accurately illustrated the same as it appears after the rolling operation. It will be readily seen that the flange is perfectly developed, and it will be obvious that it, as well as the tread, must be composed of 105 metal so condensed and worked as to render it well suited for the severe and trying ser- vice to which car-wheels are necessarily sub- jected.

Although I have shown my machines as 110 having rolls on horizontal axes, I do not limit myself to that arrangement, it being obvious that they could be vertical, so as to operate on a car-wheel while in a horizontal position, instead of on its edge, and this variation 115 would merely involve a series of radially-dis- posed legs or feet for the housing, instead of the single base illustrated by me, and an ar- rangement of the driving-gearing correspond- 120 ing to said change in position.

Having thus described my invention, I claim as new and desire to secure by Letters Patent—

1. In a machine for rolling the treads of car-wheels, the combination, substantially as hereinbefore described, of a set of circularly-arranged, positively-driven, and radially-ad- justable rolls, each having flanges or collars for laterally embracing the rim of a car-wheel, and a rolling-face corresponding in contour with the flange and tread of a car-wheel, and 125 screws for moving all of said rolls toward and from a common center.

2. The combination, substantially as herein- 130 before described, of a set of circularly-ar-

ranged and positively-driven rolls, each having a rolling-face corresponding in contour with the flange and tread of a car-wheel, the adjusting-screws, the gears on said screws, and 5 the one controlling-gear meshing with all of the screw-gears.

3. The combination, substantially as hereinbefore described, of a set of oppositely-located, circularly-arranged, positively-driven, and radially-adjustable rolls, each having a rolling-face corresponding in contour with the flange and tread of a car-wheel, and a central guiding-spindle, whereby a car-wheel blank is centrally located while its rim is being operated 10 upon and said blank revolved by said rolls.

4. The combination, substantially as hereinbefore described, of a set of positively-driven, circularly-arranged, and radially-adjustable rolls, each having a rolling-face corresponding 15

in contour with the flange and tread of a car-wheel, and a detachable clamp for laterally supporting the web and internally supporting the rim of a car-wheel while its tread is engaged by said rolls.

5. In a machine for rolling car-wheels, the combination of a set of rolls positively driven, circularly arranged, radially adjustable, and each having a rolling-face corresponding to the tread and flange of a car-wheel, and flanges or collars for embracing the side edges of a car-wheel, substantially as described; and a housing for said rolls, which is open centrally for enabling a wheel-blank or car-wheel to be inserted and removed in a sidewise position.

HERVEY W. FOWLER.
